UNITED STATES PATENT OFFICE.

EMMA M. SNYDER ROWSON, OF HADDONFIELD, NEW JERSEY.

SHIP CONSTRUCTION.

Application filed September 30, 1924. Serial No. 740,810.

To all whom it may concern:

Be it known that I, EMMA M. SNYDER ROWSON, a citizen of the United States, residing at Haddonfield, in the county of Camden and State of New Jersey, have invented new and useful Improvements in Ship Construction, of which the following is a specification.

This invention relates to ships, and an object of the invention is to provide a ship construction which will materially reduce liability of accident to the ship from striking submerged objects.

It is a well known and established fact that a large percent of shipwrecks are caused by the ship striking submerged objects, and an object of the present invention is to eliminate liability of such striking by providing means whereby a person may see through the ocean beneath the surface forwardly of the ship and in case of sighting any submerged object, may immediately telegraph or telephone its location to the pilot of the ship, permitting him to guide the ship past the object.

Another object of the invention is to provide a novel form of light, preferably of high candle power which may be used to send light rays through the water forwardly of the bow of the ship for illuminating the water, beneath the surface, when desired, and when found necessary, and also to provide means for controlling the direction of reflection of the rays.

Other objects of the invention will appear in the following detail description, and in the accompanying drawings wherein:

Figure 1 is a fragmentary view of a ship showing the improved construction.

Figure 2 is a horizontal section through a portion of the ship illustrating the lamp structures.

Figure 3 is a detail vertical section through the ship, showing the improved construction.

Figure 4 is a detail section through the ship structure.

Referring more particularly to the drawings, the improved ship construction comprises the forming of an observation compartment 1 in the bow of the ship which compartment has water-tight walls, so as to prevent seepage of moisture into the compartment. A shaft 3 through the bow of the ship is provided to permit entrance into the compartment and a ladder 4 of any ap-

proved construction is used by the operator in descending into the compartment or ascending therefrom. A door 5 is provided for closing the entrance to the observation compartment, and it is clamped in the closed position by suitable set-screws 6. A gasket 7 is preferably placed about the undersurface of the door 5 so as to permit a fluid-tight closure therefor, to prevent water from entering the compartment about the door.

An air tube 8 enters the compartment so as to supply air for the occupant and suitable wire conducting tubes 9 are provided to permit establishment of communication between the observation compartment, and the pilot house, and also to permit the supplying of the electrical current to the light used in the observation compartment.

The bow 2 of the ship is provided with a plurality of pairs of rectangular cut-out portions or openings the openings in one side of the bow being directly opposite the openings in the other side. Housings 10 are provided which project out through these openings. The housings are detachably connected in any suitable manner to the ship, in water-tight connection, and in such manner as to permit their removal when desired. The topmost pair of housings 10 have transparent windows 12 in their forward ends through which the observer may look, to permit him to see through the water beneath the surface forwardly of the ship and clearly see any submerged obstructions.

The lower pair of housings have magnifying lenses 13 in their outer ends outwardly of the ship, while levers 14 are swivelly carried by their inner ends. The levers 14 are swivelly supported by suitable bearing structures 16 formed of balls 16' attached to the levers 14 and plates 16" and they carry light bulbs 17, preferably of high candle power to their outer ends, the light rays from which are refracted through the lens 13 through the water forwardly of the ship when necessary.

From the foregoing description taken in connection with the accompanying drawings, it will be apparent that a ship constructed in accordance with the present invention will be practically safe from striking submerged articles in that an observer stationed in the observation chamber which may be looking through the transparent

panes in the upper housings 10, see any submerged articles or objects, and then by suitable communication with the pilot house, instruct the pilot of the exact location of such submerged objects and enable him to alter the course of the ship, so as to avoid a collision and the resulting accident.

It is, of course, to be understood, that the invention may be constructed in various other manners and the parts associated in different relations, and therefore, I do not desire to be limited in any manner, except as set forth in the claims hereunto appended.

What I claim is:

- 15 1. In a ship construction, a water-tight observation compartment in the bow of the hull of the ship, a plurality of observation housings carried by the bow of the hull of the ship and extending outwardly therefrom the ends of said housings exposed to the water being transparent, levers swivelly carried by certain of said housings, and illuminating means carried by said levers.
- 20 2. In a ship construction, a water-tight

observation compartment in the bow of the hull of the ship, a plurality of observation housings carried by the bow of the hull of the ship and extending outwardly therefrom the ends of said housings exposed to the water being transparent, levers swivelly carried by certain of said housings, illuminating means carried by said levers, an air pipe entering said observation compartment, a ladder extending downwardly into the compartment, and a water-tight door for closing the entrance to the compartment.

3. In a ship construction, a water-tight observation compartment in the bow of the hull of a ship, upper and lower sets of observation housings carried by the bow of the hull of the ship and extending outwardly therefrom, the upper set of housings having both their inner and their outer ends transparent, levers swivelly carried by the lower sets of housings and illuminating means carried by said levers.

In testimony whereof I affix my signature.
EMMA M. SNYDER ROWSON.
